(57) **CLAIM**

The ornamental design for a collapsible wheeled container as shown and described.

DESCRIPTION

FIG. 1 is a front top left perspective view of a collapsible wheeled container invention in a collapsed position.

FIG. 2 is a front elevation view of the invention in the collapsed position.

FIG. 3 is a rear elevation view of the invention in the collapsed position.

FIG. 4 is a left side elevation view of the invention in the collapsed position, the right side elevation view being a mirror image of the left side elevation view.

FIG. 5 is a top plan view of the invention in the collapsed position.

FIG. 6 is a bottom plan view of the invention in the collapsed position.

FIG. 7 is a front top left perspective view of the collapsible wheeled container invention in an expanded position.

FIG. 8 is a front elevation view of the invention in the expanded position.

FIG. 9 is a rear elevation view of the invention in the expanded position.

FIG. 10 is a right side elevation view of the invention in the expanded position, the left side elevation view being a mirror image of the right side elevation view.

FIG. 11 is a top plan view of the invention in the expanded position.

FIG. 12 is a bottom plan view of the invention in the expanded position.
